UNITED STATES PATENT OFFICE.

SAMUEL H. SERVITA, OF FALL RIVER, MASSACHUSETTS.

RUBBER HEEL.

1,121,141.

Specification of Letters Patent. Patented Dec. 15, 1914.

Application filed May 26, 1914. Serial No. 841,055.

To all whom it may concern:

Be it known that I, SAMUEL H. SERVITA, a citizen of Russia, residing at Fall River, in the county of Bristol, State of Massachusetts, have invented certain new and useful Improvements in Rubber Heels; and I do hereby declare the following to be a full, clear, and exact description of the invention, such as will enable others skilled in the art to which it appertains to make and use the same.

This invention relates to a rubber heel.

An object of the invention is to provide a device of this character, by means of which the shock incident to the contact of the heel with the ground during the walking operation is absorbed.

A further object of the invention is to provide a heel of such construction that the initial jar will be taken up and further motion of the foot will cause the pressure to be relieved from the initial point of contact and transferred to a cushion in the middle of the heel.

With these and other objects in view, such as will appear as the description progresses, my invention comprises the combination and arrangement of parts as herein set forth and subsequently claimed.

Referring to the drawings: Figure 1 is a plan view of the heel. Fig. 2 is a vertical sectional view of the heel. Fig. 3 is a side elevation. Fig. 4 is a bottom plan view.

Referring to the drawing by reference characters wherein like parts are indicated by like characters throughout the several views: My device comprises a heel proper 1 made of rubber having in its upper face a circular depression 2, which depression is located substantially centrally of the heel and spaced from the rear edge thereof. The depth of this depression is greater than the thickness of the heel, and in order that it may not extend completely through the heel on the under side of the same a cushion 3 is formed, which is circular in form and extends downwardly below the plane of the said heel. The lower face of the cushion 3 being substantially flat, while the sides thereof are curved, as at 4 to meet the heel.

In order that the initial jar may be taken up when the foot is placed upon the ground an elliptical depression 5 is formed in the upper face of the heel between the depression 2 and the rear edge thereof. The depth of this depression is considerably less than

the depth of the depression 2. On the under side of the heel beneath this depression 5 is a substantially elliptical cushion 6 which is joined to the cushion 3 and has a flat lower face. This latter cushion projects outwardly from the lower face of the heel, but a distance considerably less than the distance which the cushion 3 projects so that when the foot is placed upon the ground the cushion 6 yields, thus during the further movement of the foot in bringing the toe to the ground a rocking motion is produced on the heel and the shock is gradually taken up by the cushion 3, the pressure causing the material of the said cushion to be pushed upwardly in the depression 2. A series of holes 7 are formed in the sides of the heel by means of which it may be attached to a shoe.

It is to be noted that the depression 5 is of considerably less dimensions than the depression 2 and that the material between the lower face of the depression 5 and the lower face of the cushion 6 is thicker than the material between the lower face of the depression 2 and the lower face of the cushion 3. This has a peculiar advantage in that when the heel is subjected to the initial shock the pressure on the cushion 6 is great so that it is sufficient to yield and the material thereof pushed upwardly in the depression 5. However, as the heel rocks onto the cushion 3 the initial shock has been taken up and therefore the thickness of the material is decreased so that the cushion 3 will operate to take up the shock occasioned by the weight of the wearer.

From the foregoing description it may be seen that I have provided a heel having a plurality of cushions thereon, one of said cushions being of a greater yieldable character than the other, and I have further provided a heel by means of which the entire shock of walking will be absorbed.

While I have described a particular construction and illustrated the same, it is done merely for the sake of convenience for I wish it to be understood that numerous changes may be made within the scope of the invention as defined by the claims.

What is claimed is:

1. An elastic heel lift comprising a body portion having a pair of depressions in its upper face, one of said depressions being of greater area than the other and relatively deeper, cushions formed on the lower face

22
of the said body portion directly below said depression and being approximately of similar contours to the depressions, the larger of said cushions projecting outwardly from the heel a considerable distance beyond the other of said cushions, and means to secure the heel to a shoe.

2. An elastic heel lift comprising a body portion, and cushions formed on the lower side thereof, one of said cushions being located substantially centrally of the body portion and of circular formation, the lower face of said cushion being parallel to the lower face of the heel, the smaller of said 15 cushions being of elliptical formation and located between the rear edge of the first mentioned cushion and the rear of the heel, said first mentioned cushion extending outwardly beyond the plane of the second mentioned cushion.

3. An elastic heel lift comprising a body portion having a plurality of depressions

in its upper face, the said depressions being arranged from adjacent the rear of the lift forwardly on the longitudinal axis thereof and the depth of the said depressions gradually increasing forwardly, and cushions formed on the lower face of the said body portion directly below said depressions.

4. An elastic heel lift comprising a body portion, and a plurality of cushions formed on the lower sides thereof, said cushions being arranged from the rear of the heel forwardly on the longitudinal axis thereof and the distance of projection of the cushions from the face of the heel gradually increasing forwardly.

In testimony whereof, I affix my signature, in the presence of two witnesses.

SAMUEL H. SERVITA.
